UNITED STATES PATENT OFFICE.

JOHN MARSHALL, OF SWARTHMORE, PENNSYLVANIA, ASSIGNOR TO E. I. DU PONT DE NEMOURS & COMPANY, OF WILMINGTON, DELAWARE, A CORPORATION OF DELAWARE.

EXPLOSIVE FOR USE IN BLASTING CAPS.

No Drawing.

Application filed October 5, 1921. Serial No. 505,599.

To all whom it may concern:

Be it known that I, JOHN MARSHALL, a citizen of the United States, and a resident of Swarthmore, in the county of Delaware and State of Pennsylvania, have invented a certain new and useful Explosive for Use in Blasting Caps, of which the following is a specification.

This invention relates to explosive materials and particularly to the charge to be inserted in blasting caps for the purpose of exploding main charges of high explosives.

Blasting caps in the past have been made with a primer charge of mercury fulminate or of lead azide, and with a secondary charge of T.N.T., or tetra-nitro-methylaniline (tetryl), tetranitroaniline (T.N.A.), or similar substances, and have also been made with mixtures of the priming materials and the secondary charge. In general, the materials used as the secondary charge have been expensive to manufacture, being dependent on relatively expensive raw materials.

The object of my invention is to provide an explosive substance, suited for use as a secondary charge in blasting caps and for use in primers of other types, which can be prepared from raw materials of a relatively inexpensive nature.

I have discovered that an explosive substance which is admirably suited for use in blasting caps may be produced by effecting a reaction between such relatively inexpensive raw materials as oxides of nitrogen and olefines such as ethylene, propylene, etc.

The process of making the new explosive ingredients may be illustrated by the following example:

Nitrogen sesquioxide (N_2O_3) and ethylene are led simultaneously into an inert solvent, for example, diethyl ether, maintained preferably at a temperature between 5 and 20° C. One of the products of the reaction between the ethylene and the nitrogen sesquioxide precipitates from the ethereal solution in the form of a crystalline solid, which is filtered off and dried; this crystalline solid melts at 114-117° C. and contains from 26 per cent to 26.9 per cent of nitrogen.

In place of ethylene in the above example, other unsaturated hydrocarbons of the ethylene series, such as propylene, may be used; and instead of nitrogen sesquioxide alone a mixture of nitrogen sesquioxide with other nitrogen oxides may be used.

I have reason to believe that the compounds of which the specifically described product of the above example is typical are the bi-molecular pseudo-nitrosites; that is, they contain in the molecular complex, two molecules of the nitro-B-nitroso paraffin hydrocarbon, linked together through the nitroso groups. However, I wish it to be clearly understood that I do not confine myself to the structural formula thus described, but wish to cover as a part of my invention the solid product resulting from the interaction of nitrogen sesquioxide and an olefine hydrocarbon in a suitable solvent. For the sake of brevity, I use the term "pseudo-nitrosite," in describing my invention throughout this application, to mean compounds composed of two molecules of the nitro-beta-nitroso-paraffine hydrocarbon linked together thru the nitroso groups.

A blasting cap made in accordance with my invention may contain any bi-molecular pseudo-nitrosite as above described; for example, from ethylene is obtained a compound (a pseudo-nitrosite) of the following probable structure:

85

and from a propylene, the following:

90

The general structural formula for this class of substances may probably be written as follows:

95

where R represents a hydrogen or alkyl radical.

The bi-molecular ethylene pseudo-nitrosite, for example, furnishes, when associated with a suitable primer, a very powerful cap charge or composition. Thus 0.4 to 1.0 gram of the ethylene pseudo-nitrosite, the amount depending on the grade of blasting cap desired, may be pressed into the copper shell of the blasting cap in the usual man-

100

105

110

ner, and on top of this is pressed a priming charge consisting of about 0.5 gram fulminate of mercury. Instead of placing the ethylene pseudo-nitrosite and the fulminate of mercury in separate layers, they may be mixed together, equal proportions by weight, for example, of each of the two materials being used. There is produced in this way a very powerful blasting cap, which when ignited by safety fuse or by electrical means or otherwise provides an exceedingly efficient means for detonating dynamite or other high explosive.

While I have described my invention above in detail, I wish it to be understood that many changes may be made without departing from the spirit of the invention.

I claim:

1. An explosive charge comprising the normally solid product obtainable by interaction between an olefine hydrocarbon and nitrogen sesquioxide and having probably the following general formula:—

25

where R represents a hydrogen or alkyl radical.

2. An explosive charge comprising the normally solid product obtainable by interaction between ethylene and nitrogen sesquioxide and having probably the following general formula:—

40

3. An explosive charge comprising the normally solid product obtainable by interaction between an olefine and nitrogen sesquioxide and having probably the following general formula:—

45

where R represents a hydrogen radical or an alkyl radical having from 1 to 4 carbon atoms.

4. A detonator composition comprising a primary detonating compound and a bi-molecular alkylene pseudo-nitrosite.

5. A detonator composition comprising a primary detonating compound and a bi-molecular ethylene pseudo-nitrosite.

6. A blasting cap charge comprising mercury fulminate and a bi-molecular alkylene pseudo-nitrosite obtainable by interaction between an olefine hydrocarbon and nitrogen sesquioxide.

7. A blasting cap charge comprising mercury fulminate and a bi-molecular ethylene pseudo-nitrosite obtainable by interaction between ethylene and nitrogen sesquioxide.

8. A blasting cap charge comprising 1 part of mercury fulminate and from about 0.8 to 2 parts of the normally solid product obtainable by interaction of ethylene and nitrogen sesquioxide in the presence of liquid diethyl ether, said normally solid product melting at 114-117° C. and containing 26.9% of nitrogen.

In testimony whereof I affix my signature.

JOHN MARSHALL.
